CLAIM

I claim, the ornamental design for a plate, as shown and described.

DESCRIPTION

FIG. 1 is a front perspective view of a plate showing my new design;

FIG. 2 is a first side elevation view thereof;

FIG. 3 is a second side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a front perspective view of another embodiment of the plate;

FIG. 9 is a first side elevation view thereof;

FIG. 10 is a second side elevation view thereof;

FIG. 11 is a top plan view thereof;

FIG. 12 is a bottom plan view thereof;

FIG. 13 is a front elevation view thereof; and,

FIG. 14 is a rear elevation view thereof.
